UNITED STATES PATENT OFFICE.

WILLIAM E. STICKEL AND JOHN STUCKUM, OF DAYTON, OHIO.

BED-LOUNGE FRAME.

SPECIFICATION forming part of Letters Patent No. 259,341, dated June 13, 1882.

Application filed January 9, 1882. (Model.)

To all whom it may concern:

Be it known that we, WILLIAM E. STICKEL and JOHN STUCKUM, citizens of the United States, residing at Dayton, in the county of 5 Montgomery and State of Ohio, have invented a new and useful Improvement in Bed-Lounge Frames, of which the following is a specification.

Our invention relates to an improvement in 10 the ordinary bed-lounge, and is a device for elevating the bed to a level with the seat when the seat is carried forward; and it consists of a jointed bed-frame suspended on hinges at the head end, and when elevated the rear end 15 rests on the cross-piece at the foot, with pins bearing against said cross-piece to hold it in position.

The mechanism is illustrated in the accompanying illustrations, in which Figure 1 is a 20 top view of the lounge-frame. Fig. 2 is a longitudinal section of the same on the line *x*.

In the general features we build the bed-lounge as it is usually built, our invention consisting solely in the construction and manner 25 of suspending the bed.

The frame consists of two parts, A A', each 30 having side rails, and secured together by cross-slats in the usual manner. The parts are hinged together at *m*, and at *n* the part A' is hinged to the cross-piece C of the lounge or sofa frame. The cross-pieces C C' connect with a side rail 35 directly beneath the rear side rail of the seat, and are supported on feet corresponding to those of the rear rail, as illustrated at Fig. 1.

On the top of the cross-pieces are attached iron 35 plates, having tongues which enter grooves of corresponding plates attached to the under

side of the end pieces of the seat. On these plates, or otherwise, are provided projections 40 to arrest at the proper point the seat as it is drawn outward.

A series of grooved rollers may be used to support the inner end of the seat. (See roller 45 *o*, represented at Fig. 1.)

The dotted lines at Fig. 2 show the position of the bed when it is down, and in which position the seat is slid over it.

When the lounge is to be converted into a bed the seat is drawn forward. The bed is 50 then raised and the foot end is placed on the foot cross-piece, where it is held by the pin D or other suitable device. Thus the bed is elevated to the height of the seat, forming a bed 55 the width of the seat and bed combined.

Such is the state of the art that we do not 60 claim broadly the jointed bed-frame, supported front and rear, but only the combination of parts as specifically herein set forth.

Having fully described our invention, what 60 we claim, and desire to secure by Letters Patent, is—

In combination with a lounge or sofa frame, the bed-frame consisting of two parts, said 65 parts being joined by hinges attached to the under side of the rails, and the part A' being hinged to the cross-piece C of the lounge-frame as the head-support, and the pin D or equivalent to hold the bed in an elevated position, substantially as shown and set forth.

WILLIAM E. STICKEL.
JOHN STUCKUM.
